US0D1029151S

(12) **United States Design Patent** (10) **Patent No.:** **US D1,029,151 S**
(45) **Date of Patent:** **** May 28, 2024**

(54) **WEIGHT STACK PIN**

(71) Applicant: **Yongkang Yulai Industry and Trade Co., Ltd.**, Jinhua (CN)

(72) Inventor: **Junfa Zhu**, Jinhua (CN)

(73) Assignee: **Yongkang Yulai Industry and Trade Co., Ltd.**, Jinhua (CN)

(**) Term: **15 Years**

(21) Appl. No.: **29/914,295**

(22) Filed: **Oct. 16, 2023**

(51) **LOC (14) Cl.** **21-02**

(52) **U.S. Cl.**

USPC **D21/694**; D21/662; D21/673

(57) **CLAIM**

The ornamental design for a weight stack pin, as shown and described.

DESCRIPTION

FIG. 1 is a front perspective view of a weight stack pin, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view.

The broken lines in the drawings illustrate the portions of the weight stack pin, which form no part of the claimed design.

1 Claim, 8 Drawing Sheets
